Primary Examiner — Karen S Acker

(57) **CLAIM**

The ornamental design for a grill, as shown and described.

DESCRIPTION

Figure 1.1 is a top front perspective view of a grill showing my new design;

Figure 1.2 is a front elevation view thereof;

Figure 1.3 is a rear elevation view thereof;

Figure 1.4 is a right side view thereof;

Figure 1.5 is a top plan view thereof;

Figure 1.6 is a bottom plan view thereof;

Figure 1.7 is a top rear perspective view thereof; and

Figure 1.8 is a left side view thereof.

In the drawings the portions of the article shown in broken lines do not form any part of the claimed design.

1 Claim, 8 Drawing Sheets
